UNITED STATES PATENT OFFICE

170,537

COMBINED CAN AND BOTTLE OPENER

Jack H. Lanning, Washington, D. C.

Application March 9, 1953, Serial No. 23,951

Term of patent 14 years

(Cl. D22—2)

To all whom it may concern:

Be it known that I, Jack H. Lanning, a citizen of the United States, residing at Washington, in the District of Columbia, have invented a new, original, and ornamental Design for a Combined Can and Bottle Opener, of which the following is a specification, reference being had to the accompanying drawing, forming part thereof.

Figure 1 is a side elevational view of a combined can and bottle opener, showing my new design;

Figure 2 is a top plan view thereof;
Figure 3 is a front end view, and

Figure 4 is a rear end view of the same.

I claim:

The ornamental design for a combined can and bottle opener, as shown.

JACK H. LANNING.
